UNITED STATES PATENT OFFICE.

CHARLES C. MURRAY, OF HUNTINGDON, TENNESSEE.

DENTAL IMPLEMENT.

No. 909,643.

Specification of Letters Patent.

Patented Jan. 12, 1909.

Application filed September 15, 1908. Serial No. 453,094.

To all whom it may concern:

Be it known that I, CHARLES C. MURRAY, a citizen of the United States, residing at Huntingdon, in the county of Carroll, State 5 of Tennessee, have invented an Improvement in Dental Implements of which the following is a specification.

My invention is an improved implement or tool for use in inlay work.

As is well known to those acquainted 10 with the dental art in its present development, inlays consisting of plugs of porcelain, gold, glass, vulcanized rubber or other suitable material, are formed for filling 15 tooth cavities, the same being cemented therein. One of the usual methods for producing cast inlay work, consists in pressing wax into the tooth cavity, which is to be filled or plugged, then a metal pin is slightly 20 heated and inserted in the wax that fills the cavity. Next the pin and the wax are chilled by a jet of cold water, by which the pin is set and held in the wax with due firmness. This enables the dentist to remove the 25 wax model while adhering to the pin. The dentist then makes a wax cone of the desired size, the same being formed around the pin just above the wax model. The whole, that is to say, the cone, the pin, and 30 the model, are then inserted to the required depth in some suitable fire-proof compound. The latter is then subjected to heat, whereby 35 the wax is melted and thus removed from the investment, a hole being left in the top of the latter for the reception of the plastic material or metal which is to be heated for filling the space previously occupied by the wax model. By my invention, the use of such wax cone is dispensed with and thus 40 an important saving in time and labor is effected.

In carrying out my invention, I employ 45 a hollow conical metal body having a hole in the apex for reception of the pin which is to hold the wax model, and the body of the cone is provided with a handle and a clasp adapted to secure the pin detachably, all as hereinafter more particularly set forth.

In the accompanying drawing, Figure 1 50 is a perspective view of the entire implement, the pin being separated from the other parts. Fig. 2 is a side view of the entire implement, the pin being held in its normal position. Fig. 3 is a longitudinal 55 section of the parts in the position shown

in Fig. 2. Fig. 4 is a cross section on the line 4—4 of Fig. 2.

The numeral 1 indicates the hollow, conical, metal body of the implement, the same being provided at its apex with a hole 2 60 adapted to receive the shank 3 of the pin. The latter is provided at its outer end with a conical enlarged head 3^a, and the shank is also provided with a circumferential groove 3^b. The cone 1 is provided interiorly, at 65 about the middle of its length, with a cross-bar or bracket 4 which has a central opening adapted to receive the shank 3 of the pin and in which the same may slide freely. A combined handle and shank is connected with 70 the cross bar 4. The same consists of a plate 5 which is formed rigidly with the cross bar, and a pivoted spring clasp 6, whose inner end is curved inward to form a catch 6^a adapted to engage the circumferential groove 75 3^b in the pin shank 3. The part 6 is pivoted centrally to the plate 5, and a spring 7 is interposed between their outer ends so that the catch 6^a is held normally engaged with the pin, the head 3^a of the latter abutting the 80 apex of the cone, as shown in Figs. 2, 3.

In the practical use of my invention, it is manipulated as follows: The head 3^a of the pin having been inserted in the wax model and secured therein, it, with the wax model 85 adhering, is inserted in the cone 1 in the manner indicated in Figs. 2, 3. As is apparent, when thus inserted the shank of the pin is automatically engaged by the catch 6^a, and thus the adhering model is held securely 90 in place, the base of the head 3^a abutting the edge of the hole 2 in the cone. The whole is then invested in some plastic fire-proof compound, and as soon as the same has set, the cone and pin are withdrawn, it being only 95 necessary, for this purpose, to apply slight lateral pressure to the handle formed by the parts 5, 6, and to give the cone a slight rotary movement at the same time. This removal is accomplished in almost an instant of time, 100 whereas, by the old method it is necessary to melt out the cone of wax whose place and function are substituted by my metal cone 1. Besides this, the whole of the investment is left clean and clear of any portion of the 105 wax. The hole left in the investment then serves for reception of the porcelain or other material which is to form the inlay, and which requires to be heated to a certain degree.

The function of the enlarged head of the pin in addition to holding the wax model, is to prevent the investing material from entering the cone when the latter is being inserted therein. In view of its secondary function, the pin is commonly denoted a sprue pin, or sprue-hole pin.

What I claim is:

1. The improved dental implement, comprising a hollow body having a hole at the apex, a sprue pin having an enlarged head, the shank thereof being adapted to slide in the said hole, a combined handle and pin catch connected with the body, substantially as described.

2. The improved dental implement, com-

prising a hollow cone having a hole in the apex and a rigid bracket within the same, a pin having an enlarged head and a shank adapted to slide in said hole and through the bracket, a handle proper which is rigidly connected with the bracket, and a pin clasp comprising a plate pivoted to the handle and adapted for engagement with the pin, for holding its enlarged head in contact with the outer side of the cone apex, substantially as described.

CHAS. C. MURRAY.
